ATTORNEY

UNITED STATES PATENT OFFICE.

WILLIAM M. FERGUSON, OF FRESNO, CALIFORNIA.

DESIGN FOR A RUG.

60,854.

Specification for Design.

Patented Apr. 18, 1922.

Application filed May 16, 1921. Serial No. 470,008. Term of patent 7 years.

To all whom it may concern:

Be it known that I, WILLIAM M. FERGUSON, a citizen of the United States, residing at Fresno, in the county of Fresno and State of California, have invented a new, original, and ornamental Design for Rugs, of which the following is a specification, reference being had to the accompanying drawings, forming part thereof.

The figure is a plan view of a rug, showing my new design.

I claim:

The ornamental design for a rug, as shown.

WILLIAM M. FERGUSON.
